US00D465205S

(12) **United States Design Patent** (10) Patent No.: **US D465,205 S**
Orpilla et al. (45) Date of Patent: ** Nov. 5, 2002

(54) **ELECTRONICS HOUSING ELEMENTS**

(75) Inventors: **Kris Orpilla**, San Francisco, CA (US);
Charles Curb bun, La Costa, CA (US);
Kevin Simmons, San Diego, CA (US);
Russell L. Machado, San Diego, CA
(US)

(73) Assignee: **Pulse Engineering**, San Diego, CA
(US)

(**) Term: **14 Years**

(21) Appl. No.: **29/141,570**

(22) Filed: **May 9, 2001**

(51) LOC (7) Cl. **13-03**

(52) U.S. Cl. **D13/154**

(58) Field of Search D13/133, 146,
